(57) **ABSTRACT**

A body-conforming booster cushion seat having a malleable filler material so as to permit the cushion to conform to the body shape of a user when the user is seated thereon. The booster cushion seat includes a strap for securing the cushion to the chair, and the height of the cushion may be adjusted by adjusting the tension on the strap. The bottom of the cushion is provided with a textured base to prevent slipping when the textured base contacts a corresponding surface, and a safety belt is included to secure a juvenile user in place on the booster cushion seat.

NON-SLIP BODY-CONFORMING BOOSTER
CUSHION SEAT

FIELD OF THE INVENTION

The present intention relates to a non-slip body-conforming booster cushion seat. More particularly, the present invention is a booster cushion seat comprising an outer portion having four sides, a substantially square bottom portion or base, and a depressed upper portion, the substantially square bottom portion or base having a textured surface to prevent slipping, and the booster cushion seat having a malleable filler material to as to permit the cushion to conform to the body shape of a user. The booster cushion seat is further provided with a safety belt to secure a juvenile user in place on the booster cushion seat.

SUMMARY OF THE INVENTION

A non-slip body-conforming booster cushion seat comprising an outer portion having four sides, each of the four sides being comprised of a substantially trapezoid shaped panel, the largest side of each trapezoid shaped panel attaching to the bottom portion or base, a substantially square bottom portion or base, and a depressed upper portion which forms the central section of the booster cushion seat, the substantially square bottom portion or base having a textured surface, preferably with a rubber or similar texture, to prevent slipping when placed against a substantially flat surface, and the booster cushion seat having a malleable filler material to as to permit the cushion to conform to the body shape of a user or, more particularly, to the buttock area of a juvenile user. The depth of the depressed central section may be adjusted by varying the degree of tightness with which the strap is pulled and secured around the chair back. When the strap is pulled tightly around a chair back, the depressed central section is raised, and when the strap is secured in a loose fashion around a chair back, the depressed central section is lowered. Thus, the strap allows the user to be positioned higher, such as for greater visibility in a theater, or lower, to permit the user seated on a dining-type chair in combination with the booster cushion seat to fit under a dining table. Additionally, the degree of tightness may be altered to accommodate the size of the user. The strap may be pulled tighter to create a smaller depressed central section to accommodate a small child user or, alternatively, the strap could be secured in a more loose fashion to accommodate a larger user. In this way, the height of the cushion may be adjusted by adjusting the tension on the strap. Once the user is seated within the depressed central section of the booster cushion seat with the booster cushion seat conformed to the body of the user, the rearmost trapezoid shaped panel may provide a support for the user's lower back. The booster cushion seat is further provided with a safety belt comprising a nylon webbing or similar type material, which safety belt is adapted to secure a juvenile user in place on the booster cushion seat. The safety belt is substantially T-shaped, including a perpendicularly extending leg and a cross member. The perpendicularly extending leg of the T has a first and second end thereon, the first end being attached to the booster cushion seat at a point midway along one of the trapezoid shaped panels. The cross member of the T has a first and second end thereon. The first end of the cross member is provided with a female receiving member of a buckle, and the second end of the cross member is provided with a male member of a buckle. The female member of the buckle is adapted to receive the male member to secure the buckle in place. The cross member of the T-shaped safety belt is of

2

sufficient length to encompass the torso of a toddler-aged child or other juvenile user. Additionally, the cross member of the safety belt preferably is provided with a means for adjusting the length of the belt to accommodate a growing child.

5 Alternatively, the booster cushion seat could be sized to accommodate an adult user by lengthening the adjustable safety belt.

BRIEF DESCRIPTION OF THE DRAWINGS

10 FIG. 1 is a perspective view of the non-slip body-conforming booster cushion seat of the present invention showing the adjustable tabs in an open position.

15 FIG. 2 is a rear view of the non-slip body-conforming booster cushion seat of the present invention showing the adjustable tabs in a closed position around the back of a chair.

20 FIG. 3 is a bottom view of the non-slip body-conforming booster cushion seat of the present invention showing the non-slip textured base and showing the adjustable tabs in an open position.

25 FIG. 4 is a top view of the non-slip body-conforming booster cushion seat of the present invention showing the adjustable tabs in an open position and the T-shaped belt in an open position.

30 FIG. 5 is a perspective view of the non-slip body-conforming booster cushion seat of the present invention showing the booster cushion seat in position on a dining-type chair when viewing the chair from the front.

35 FIG. 6 is a perspective view of the non-slip body-conforming booster cushion seat of the present invention showing the booster cushion seat in position on a dining-type chair when viewing the chair from the rear.

40 FIG. 7 is a perspective view showing a rear view of the non-slip body-conforming booster cushion seat of the present invention showing a juvenile user positioned on the booster cushion seat with the T-shaped safety belt being disposed around the torso of the juvenile user.

DETAILED DESCRIPTION OF THE PREFERRED
45 EMBODIMENTS

Referring to the drawings in detail, FIG. 1 shows a perspective view of a non-slip body-conforming booster cushion seat 10 comprising a substantially square base 16 having four sides thereon and which is provided with a textured surface thereon to prevent the textured base from slipping when the textured base contacts another surface, such as a chair seat (not shown in this figure). The textured base is connected by a seam (not numbered) to four fabric sides 22, 24, 26 and 28. 50 Each of the four fabric sides 22, 24, 26 and 28 is provided with a top edge, a first side edge, a second side edge, and a top edge (not numbered), and each of the four fabric sides 22, 24, 26 and 28 is attached at the bottom edge thereof to one of the four sides of the substantially square textured base 16. Each of the 55 fabric sides 22, 24, 26 and 28 tapers convergingly inward from the point where the side attaches to the textured base 16 to form a substantially trapezoid shape (not numbered). The first and second ends of each of the trapezoid shaped sides are joined to an adjacent side by a seam (not numbered) such that the first side edge of the fabric side 22 meets the second side edge of fabric side 28, the first side edge of fabric side 24 meets the second side edge of fabric side 22, the first side edge of fabric side 26 meets the second side edge of fabric side 24, and the first side edge of fabric side 28 meets the second side edge of fabric side 26. The top of each trapezoid shaped fabric side 22, 24, 26 and 28 is stitched to a central substantially circular portion which, when all portions are interconnected,

forms a substantially pyramid-type shape with a depressed central section 30 which depressed central section 30 is adapted to receive the buttocks of a juvenile user or small adult user (not shown in this figure). Two fabric arms 18 and 20 are attached to the seam which joins fabric sides 22 and 28 and 24 and 22, respectively. The fabric arms 18 and 20 are provided with a hook and loop or other type of fastening device 32 and 34, respectively, at the ends thereof. A T-shaped safety belt comprising a horizontal leg 14 and a cross member 12, and preferably made from a webbing-type strap material, is attached at a central location along the fabric side 22. The cross member 12 may be inserted through the horizontal leg 14, sewn onto the horizontal leg 14, or otherwise connected to the horizontal leg 14. The cross member 12 of the T-shaped safety belt has a first end and a second end (not numbered). The first end of the cross member 12 is provided with a female receiving member 36 of a commercially available buckle-type device. The second end of the cross member 12 is provided with a male member 38 of a commercially available buckle-type device, such that when the male member 38 is inserted into the female receiving member 36, the cross member 12 is secured in a circular form adapted to encircle the waist or torso of the juvenile user or small adult user (not shown in this figure). The T-shaped safety belt may be alternatively provided with hook and loop, plastic or other type fasteners at each of its respective ends to secure the user adjustably on the booster cushion. The T-shaped safety belt may be provided with a means for lengthening the cross member 12 and/or the horizontal leg 14 of the T-shaped safety belt to permit customized adjustment to fit a plurality of users. The two fabric arms 18 and 20 are adapted to wrap around the back of a chair (or other seating) and connect by means of hook and loop fasteners 32 and 34, respectively, (or other means). Thus, the arms 18 and 20 form a strap for the purpose of securing the booster cushion seat 10 on to the chair (or other seating) to further prevent slippage. When the booster cushion seat 10 is placed onto a surface, such as a chair (not shown in this figure), the fabric arms 18 and 20 wrap around the chair back (not shown in this figure), overlap each other at their respective ends, and the first hook and loop (or other type) fastener 32 contacts the second hook and loop (or other type) fastener 34 to secure the fabric arms 18 and 20 in place. The substantially square textured base 16 of the booster cushion seat 10 comprises a non-slip or textured surface (as indicated above) to prevent the booster cushion seat 10 from moving when placed in contact with a polished or "slick" surface such as a wooden chair, vinyl upholstered seat, or the like. The booster cushion seat 10 is filled with polystyrene beads or similar filling to create the feel and malleability of a bean bag. This filling permits the booster cushion to conform to the shape of the user, allowing the buttocks of the user to sink into the seat for greater stability and comfort. The booster cushion seat 10 is adapted for use by a juvenile user or a small adult and may be employed in a plurality of uses where a user desires to be elevated to a higher position, such as at the dinner table, in a restaurant booth/chair, or in a theater setting.

FIG. 2 shows a non-slip body-conforming booster cushion seat 10 having the strap formed by the two fabric arms 18 and 20 wrapped around the back of a chair 42 and connected by means of the hook and loop fasteners 32 and 34, respectively, for the purpose of securing the booster cushion seat on to the chair. The booster cushion seat 10 is received on top of the chair seat 44 such that the textured base 16 of the booster cushion seat 10 contacts the chair seat 44. The textured base 16 is adapted to prevent the booster cushion seat 10 from slipping when placed into contact with the chair seat 44 as indicated above. The fabric arms 18 and 20 wrap around the

chair back 42, overlap each other at their respective ends, and the first hook and loop fastener 32 contacts the second hook and loop fastener 34 to secure the fabric arms 18 and 20 in place around the chair back 42. The depressed central section 30 (not shown in this figure) may be slightly elevated by tightening the strap, that is, by wrapping the fabric arms 18 and 20 in tight fashion and securing them in the tight position by means of the hook and loop fasteners 32 and 34, respectively, to accommodate a smaller user. Conversely, the 10 depressed central section 30 (not shown in this figure) may be further depressed by loosening the strap, that is, wrapping the fabric arms 18 and 20 in loose fashion and securing them in the loose position by means of the hook and loop fasteners 32 and 34, respectively, to accommodate a larger user. Thus, the 15 height of the cushion may be adjusted by adjusting the tension on the strap.

FIG. 3 shows a bottom view of the non-slip body-conforming booster cushion seat 10 having a substantially square shaped textured base 16, as indicated above. A first fabric arm 20 is provided with a first hook and loop type fastener 32, and a second fabric arm 18 is provided with a second hook and loop type fastener 34. In this figure, the first and second fabric arms 18 and 20, respectively, are in an unattached or loose position.

FIG. 4 shows a top view of the non-slip body-conforming booster cushion seat 10 wherein the first and second fabric arms 18 and 20, respectively, are in the unattached or loose position. A T-shaped safety belt comprising a horizontal leg 14 and a cross member 12 is shown in an open, extended position. The first end of the cross member 12 of the T-shaped safety belt is provided with a male member 38 of a commercially available type buckle. The second end of the cross member 12 of the T-shaped safety belt is provided with a female receiving member 36 adapted to receive the male member 38 to form a continuous loop around the waist or torso of a user (not shown in this figure).

FIG. 5 shows a perspective view taken from the front of a non-slip body-conforming booster cushion seat 10 placed on a dining-type chair 40. The substantially square textured base 16 is in contact with the chair seat 44. The fabric arms 18 and 20 (number 20 not shown in this figure) are engaged by means of their hook and loop type fasteners 32 and 34, respectively (not shown in this figure), so that the fabric arms 18 and 20 form a strap encircling the chair back to secure the booster cushion seat 10 in place.

FIG. 6 shows a perspective view taken from the rear of a non-slip body-conforming booster cushion seat 10 placed on a dining-type chair 40, the substantially square textured base 16 being in contact with the chair seat 44. The fabric arms 18 and 20 are engaged by means of their hook and loop type fasteners 32 and 34, respectively (not shown in this figure), the fabric arms 18 and 20 forming a strap encircling the chair back to secure the booster cushion seat 10 in place.

FIG. 7 shows a perspective view taken from the front of a non-slip body-conforming booster cushion seat 10 placed on a dining-type chair 40 with a juvenile user 46 seated atop the depressed central section 30. The substantially square textured base 16 contacts the chair seat 44. The fabric arms 18 and 20 are engaged by means of their hook and loop type fasteners 32 and 34, respectively (not shown in this figure), the fabric arms 18 and 20 forming a strap encircling the chair back to secure the booster cushion seat 10 in place. The juvenile user or small adult user is seated atop the booster cushion seat 10 with her buttocks being received in the depressed central section 30 and her legs extending from the depressed central section 30 over the third (or front) fabric side 26 (not numbered in this figure). The horizontal leg 14 of

the T-shaped safety belt extends upwardly from its origin on the fabric side 22 until the cross member 12 is brought to a point substantially level to the torso or waist of the user. The first and second ends of the cross member 12 are brought about the waist of the user to encircle the waist of the user and the male member 38 is inserted into the female receiving member 36 to secure the T-shaped safety belt in place. The booster cushion seat 10 is filled with polystyrene beads or alternate filler material such that the booster cushion seat 10 comprises a malleable shape which malleable shape is adapted to conform to the body of a user 46 when the user 46 is seated on the booster cushion seat 10 to provide maximum comfort, security, and stability to the user 46.

While FIGS. 1 through 7, inclusive, depict the various positions which may be achieved with the non-slip body-conforming booster cushion seat 10 of the present invention, it should be apparent that other and further modifications of the present invention, apart from those shown or suggested herein, may be made within the spirit and scope of this invention.

What is claimed is:

1. A booster seat to support a user in an adult-sized chair, the chair having a generally horizontal seat and a generally vertical back, the booster seat comprising:

a cushion comprising a flexible enclosure and a filler material contained in the enclosure so that the cushion is malleable, wherein the cushion has a height and comprises a top, a bottom, and a side wall extending therebetween, the cushion also having a front and a rear, wherein the top of the cushion is characterized by a malleable, depressed central section having a depth and being sized to receive the buttocks of the user, and wherein the cushion is sized and shaped to be received in the seat of the chair, the overall size of the cushion being such that it does not substantially overhang the seat of the chair;

a strap extending from the side wall of the cushion and sized and positioned to adjustably secure the cushion to the back of the chair, wherein the strap is extendable a distance beyond the side wall of the cushion, the strap being configured so that the cushion can be secured to the chair without changing the height of the cushion and so that adjusting the tension on the strap changes the height of the cushion by changing the depth of the depressed central section.

2. The booster seat of claim 1 wherein the bottom of the cushion has a textured surface to prevent slipping when placed in the seat of the chair.

3. The booster seat of claim 1 wherein the top of the cushion comprises a top panel and the depressed central section is formed in the top panel.

4. The booster seat of claim 1 wherein the side wall comprises four side panels, each being comprised of a substantially trapezoid shaped fabric panel, wherein the bottom of the cushion comprises a substantially square bottom panel, wherein the top panel is generally round, wherein the largest side of each trapezoid shaped side panel attaches to the substantially square bottom panel, wherein the smaller side of each trapezoid shaped side panel attaches to the top panel, so that the cushion is generally square in horizontal section and generally frusto-conical in vertical section.

5. The booster seat of claim 1 wherein the strap comprises two fabric arms each having a first end attached to the cushion and a free end, and wherein the free ends are adjustably connectable to each other.

6. The booster seat of claim 5 wherein the first ends of the two fabric arms are attached to the side wall of the cushion in

spaced apart positions on or near the rear of the cushion so that the arms can encircle the entire back of the chair.

7. The booster seat of claim 6 wherein the free ends of the two fabric arms are long enough to overlap each other and are provided with mating halves of hook-and-loop fastener material so that the tension on the strap can be increased and decreased by increasing or decreasing the overlapping area of the free ends of the fabric arms.

8. The booster seat of claim 1 wherein adjusting the tension on the strap also adjusts the depth of the depressed central section of the top of the cushion.

9. The booster seat of claim 1 further comprising a safety belt adapted to secure the user in the cushion.

10. The booster seat of claim 9 wherein the safety belt is a T-shaped belt, the safety belt having a cross member and a leg extending perpendicularly thereto, the leg of the T-shaped belt having a first and second end, the first end being attached to the booster cushion, the cross member of the T-shaped belt having a first and second end connectable to each other.

11. The booster seat of claim 10 wherein the first and second ends of the cross member are adjustably connectable to accommodate different size users.

12. The booster seat of claim 1 wherein the strap is sized to completely encircle the back of the chair.

13. The booster seat of claim 1 characterized as being free of rigid structural members that extend above the cushion.

14. A seating assembly for a user, the assembly comprising:

an adult-sized chair comprising a generally horizontal seat and a generally vertical back, the seat having a peripheral edge;

a booster seat receivable in the seat of the chair, the booster seat sized so that it does not substantially overhang the peripheral edge of the seat of the chair, and wherein the booster seat comprises:

a cushion comprising a flexible enclosure and a filler material contained in the enclosure so that the cushion is malleable, wherein the cushion has a height and comprises a top, a bottom, and a side wall extending therebetween, the cushion also having a front and a rear, wherein the top of the cushion is characterized by a malleable, depressed central section having a depth and being sized to receive the buttocks of the user;

at least one strap extending from the sidewall of the cushion and sized and positioned to adjustably secure the cushion to the back of the chair, wherein the strap is extendable a distance beyond the side wall of the cushion, the strap being configured so that the cushion can be secured to the chair without changing the height of the cushion and so that adjusting the tension on the strap changes the height of the cushion by changing the depth of the depressed central section.

15. The seating assembly of claim 14 wherein the bottom of the cushion has a textured surface to prevent slipping when placed in the seat of the chair.

16. The seating assembly of claim 14 wherein the top of the booster seat cushion comprises a top panel.

17. The seating assembly of claim 16 wherein the side wall of the booster seat cushion comprises four side panels, each being comprised of a substantially trapezoid shaped fabric panel, wherein the bottom of the cushion comprises a substantially square bottom panel, wherein the top panel is generally round, wherein the largest side of each trapezoid shaped side panel attaches to the substantially square bottom panel, wherein the smaller side of each trapezoid shaped side panel attaches to the top panel, so that the cushion is generally square in horizontal section and generally frusto-conical in vertical section.

panel attaches to the top panel, so that the cushion is generally square in horizontal section and generally frusto-conical in vertical section.

18. The seating assembly of claim **16** wherein adjusting the tension on the strap of the booster seat cushion also adjusts the depth of the depressed central section of the top of the cushion.

19. The seating assembly of claim **14** wherein the strap of the booster seat cushion comprises two fabric arms each having a first end attached to the cushion and a free end, and wherein the free ends are adjustably connectable to each other.

20. The seating assembly of claim **19** wherein the first ends of the two fabric arms of the booster seat cushion are attached to the side wall of the cushion in spaced apart positions on or near the rear of the cushion so that the arms can encircle the entire back of the chair.

21. The seating assembly of claim **20** wherein the free ends of the two fabric arms are long enough to overlap each other and are provided with mating halves of hook-and-loop fas-

tener material so that the tension on the strap can be increased and decreased by increasing or decreasing the overlapping area of the free ends of the fabric arms.

22. The seating assembly of claim **14** wherein the booster seat further comprises a safety belt adapted to secure the user in the cushion.

23. The seating assembly of claim **22** wherein the safety belt is a T-shaped belt, the safety belt having a cross member and a leg extending perpendicularly thereto, the leg of the **10** T-shaped belt having a first and second end, the first end being attached to the booster cushion, the cross member of the T-shaped belt having a first and second end connectable to each other.

24. The seating assembly of claim **23** wherein the first and **15** second ends of the cross member are adjustably connectable to accommodate different size users.

25. The seating assembly of claim **14** wherein the booster seat is characterized as being free of rigid structural members that extend above the cushion.
